UNITED STATES PATENT OFFICE.

JOHN A. McINTYRE, OF DENVER, COLORADO, ASSIGNOR TO THE McINTYRE PUMP COMPANY, OF DENVER, COLORADO, A CORPORATION OF COLORADO.

INTERNAL-COMBUSTION PRESSURE-PUMP.

1,333,265.

Specification of Letters Patent.

Patented Mar. 9, 1920.

Application filed February 5, 1918. Serial No. 215,517.

To all whom it may concern:

Be it known that I, JOHN A. McINTYRE, citizen of the United States, residing at the city and county of Denver and State of Colorado, have invented certain new and useful Improvements in Internal-Combustion Pressure-Pumps; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in pumps in which the water raising force results from explosions in cylinders with which the pump is provided, these cylinders being supplied with an explosive mixture, the latter being ignited at properly timed intervals, whereby explosions alternately occur in the two cylinders. Pistons working in these cylinders are operated by a motor or engine of small capacity, being just sufficient to keep the cylinders in motion, the power for raising or pumping the water being exerted by the aforesaid explosive force.

Provision is made for locking the pistons against the recoil stress exerted by the explosions, whereby undue strain on the mechanism is avoided. Furthermore, provision is made for exhausting the burned products which pass with the explosive force into the chamber or compartment where the water is acted upon and whereby the pressure in this chamber after each explosion is atmospheric only, since said chamber is open to the atmosphere both for the admission of the atmospheric air and for the exhaust of any burned gases which may have entered the chamber.

The explosions occur in each cylinder before the piston therein has reached the head adjacent the explosion compartment. Consequently, an opportunity is given for scavenging the cylinder of burned gases which are trapped beyond the outlet for the explosive force after the piston passes said outlet. These remaining burned products by reason of the grooved construction of the cylinder are allowed to pass to the opposite side or rear thereof, whereby they may escape to the atmosphere either through the outlet for the explosive force by way of

the water chamber or at the opposite extremity of the cylinder which is open for the purpose.

Having briefly outlined my improvement I will proceed to describe the same in detail, reference being made to the accompanying drawing in which is illustrated an embodiment thereof. In this drawing:

Fig. 1 is a top plan view of my improved internal combustion pressure pump.

Fig. 2 is a vertical longitudinal section taken through the pump on the line 2—2, Fig. 1.

Fig. 3 is a fragmentary view illustrating the means for locking a piston against the stress of the explosive force to prevent undue strain on the piston operating mechanism, the parts being shown on a much larger scale than in Fig. 2.

Fig. 4 is a section taken on the line 4—4, Fig. 1, cutting the well, the water chamber which receives the explosive force and the stand pipe through which the water rises in response to said force, the balance of the apparatus being shown in side elevation.

Fig. 5 is a top plan view of a valve for controlling the exhaust to the atmosphere from the water chamber which receives the explosive force, the parts being shown on a larger scale than in the other views.

Fig. 6 is a section taken on the line 6—6, Fig. 5, the parts being shown on a still larger scale.

Fig. 7 is a section taken on the line 7—7, Figs. 1 and 2, the parts being shown on a larger scale.

Fig. 8 is a fragmentary detail view of the piston rod or stem, illustrating the swinging contact pendants through the medium of which the circuits of the ignition mechanism are closed, the parts being shown on a larger scale.

Fig. 9 is a fragmentary view looking in the direction of arrows 9, Fig. 8.

Fig. 10 is a cross section of one of the pendent contacts taken on the line 10—10, Fig. 8, shown on a larger scale.

The same reference characters indicate the same parts in all the views.

Let the numeral 5 designate each of two cylinders which are mounted on a suitable bed or foundation 6, each cylinder having a piston 7 mounted to reciprocate therein, the two pistons being respectively secured to the opposite extremities of a connecting rod

or stem 8 which passes through stuffing boxes 9 with which the inner heads 10 of the cylinders are equipped. Each cylinder is provided near its inner head with an inlet 12 for the entrance of explosive mixture, this mixture being introduced by way of a pipe 13 having an inwardly opening check valve 14 which unseats to permit the entrance of the explosive mixture and which 10 seats as soon as the explosion occurs in the compartment 15 of each cylinder.

These pistons are operated from a small motor or engine 16 which serves to rotate a shaft 17 provided with a worm 18 which 15 operates a worm wheel 19 carrying a wrist pin 20 offset from its center sufficiently to give the necessary throw or travel to the pistons. This wrist pin is connected by means of a pitman 21 with a cross head 22 mounted 20 in a suitable casing 23 and connected by means of an arm 24 with the piston rod 8 which is provided with two horizontally disposed arms 25 whose outer extremities are provided with swinging pendants 26, 25 each having an insulating cover 27 and an exposed contact 28 integral with the member 26 (Fig. 10), and forming a good conductor for the electric current.

The explosions in the two cylinders occur in the compartments 15 or the compartments adjacent the inner heads 10 of these cylinders. The two contacts 26 are so arranged that their metal parts 28 are on their inner surfaces or the surfaces toward the 30 center of the machine when the structure is in the position illustrated in Fig. 1, in which this contact mechanism is shown, but on a very small scale. As the pistons move toward the right, the left hand contact 26 will strike a coöperating contact 29, its metal part 28 engaging the same and closing a circuit by way of rod 8 through a spark plug 30, whereby an explosion occurs in the left hand cylinder 5 and at the right of the 40 piston. Again, if the pistons move toward the left in the cylinders, the right hand contact 26 will engage with its metal part 28 another coöperating contact 29 which will close the circuit by way of rod 8 through 45 a spark plug 31 and produce an explosion in the right hand cylinder at the left of the piston. The pendent contacts 26 in Fig. 1 are so arranged that they engage the coöperating contacts 29 shortly after the pistons within the cylinders have left the outer 50 extremities or heads of the cylinders, whereby the explosion occurs with very little compression of the charge of the explosive mixture.

60 It will be understood that as either piston 7 travels toward the outer extremity or head of the cylinder, a charge of explosive mixture is drawn into the compartment 15 of the cylinder by virtue of the partial 65 vacuum produced by such movement of the

piston, the charge of explosive mixture passing through the check valve controlled inlet pipe 13, then as the piston begins its inward movement it would immediately begin the compression of the gas charge; but I have found from experience that it is not necessary to compress the gas charge to any great extent or even at all in order to obtain the necessary explosive force for water raising. Hence, as before stated, the pendant contacts 26 are so arranged with reference to the coöperating contacts 29 that the explosions will occur shortly after the respective pistons begin their return movements, or their movement toward the inner 75 heads of the cylinders.

Each cylinder is provided near its inner head with an outlet port 32 for the explosive mixture, this port being normally closed by a check valve 33 provided with a stem 34 which is surrounded by a spring 36 which engages a stop 35 on one extremity while its opposite extremity bears against a tension nut 37 which is screwed into the outer extremity of a casing member 38, the latter being connected with a screw cap 39 which is screwed into the main casing 40 of the valve 33. This valve is held seated with sufficient force to maintain the port 32 closed at all times except when the explosion occurs and then the valve is unseated to allow the explosive force to pass out of the cylinder and into a water chamber 41 by way of a conduit 42. There are two of these conduits 42, one in communication 45 with the main valve casing 40 of each cylinder. These conduits 42 unite in a union 43 from which a single conduit 44 leads downwardly and communicates at its lower extremity with the chamber 41. This chamber is submerged either wholly or partly in the water 45 of the well 46 or of the stream or other source from which the pump is taking its supply. The chamber is provided at its lower extremity with an opening 47 which is normally closed by a gravity check valve 48 vertically movable on a stem 49, whereby the water within the chamber 41 will assume the same level as in the well or other source. As illustrated in the drawing, the chamber 41 is supported by the pipe or conduit member 44 whose lower extremity is secured thereto. It will be understood, however, that any suitable means may be employed for supporting the chamber 41 within the source of supply.

The action of the explosive force on the water in the chamber 41 causes the same to rise within the funnel shaped lower extremity 50 of a stand pipe 51, the lower part 52 of the funnel shaped member being cylindrical and having an opening 53 in its bottom which is normally closed by a check valve 54 which is vertically slidable on a stem 55. As the explosion occurs, the water pressure 130

opens the check valve 54 and the water rises through the stand pipe 51 and is discharged at the upper extremity of the latter in a continuous stream when the pump is regularly in operation, since the explosions occur alternately in the compartments 15 of the two cylinders.

Attention is called to the fact that the chamber 41 is in communication with the atmosphere by way of a pipe member 56 whose lower extremity is open and is connected with the union 43 and whose upper extremity is expanded, as shown at 57, and equipped with a plate 58 provided with a number of ports 59 which are regulated by a rotary valve disk 60 having a stem 61 which is connected with an oscillatory arm 62, the latter in turn being connected with the piston stem 8 about midway of the latter, as shown at 63 (see Fig. 1). A pin on the piston stem enters a slot 64 in the arm 62, so that as the piston reciprocates the necessary oscillatory movement is imparted to the arm to regulate the ports 59 with which the plate 58 is provided, the construction and arrangement of the parts being such that the upper extremity of the pipe 56 is open to the atmosphere at all times except when the explosions occur in the cylinders. At such times it is, of course, necessary in order that the explosive force may be utilized to the best advantage in raising the water through the stand pipe that any escape of such force to the atmosphere is cut off. As soon, however, as the explosion occurs and has spent its force on the water in the chamber 41, the rotary valve 62 is shifted to open the pipe 56 to the atmosphere, whereby any undue pressure in the chamber 41 is relieved, the burned products of combustion which have entered said chamber being also allowed to escape to the atmosphere. Hence, as the pressure within the chamber and the well or other source of supply is the same, namely, atmospheric, the water within the chamber will resume its normal level in time for the next explosion.

After the explosion has occurred in either cylinder, the piston moves inwardly toward the opposite head and scavenges the burned products of combustion which are forced out through the port 32, until the piston closes or passes this port, after which the remainder of these gases will escape through a circumferential groove 66 and short longitudinal grooves 67 with which the inner extremity of each cylinder is provided, the longitudinal grooves being long enough to reach beyond the piston when the latter is at its innermost limit of movement, so that these gases may pass into the compartment beyond the piston and escape either through the port 32 or at the outer extremity of the cylinder whose head 68 may be provided with openings 168 for the purpose. In fact,

the outer extremities of the cylinders may if desired be entirely open, or if they are closed, the piston stem may be hollow and open at its extremities to prevent any compression between the outer heads of the cylinders and the pistons. In this event the hollow piston stem may have one or more openings centrally arranged, which will always be exposed to the atmosphere.

In order to relieve the mechanism for operating the pistons from undue stress or strain due to the explosions in the cylinders which occur when the pistons are traveling inwardly, I provide means for positively locking the pistons against return movement at the instant any explosion occurs. This mechanism consists of a couple of links 69 which are pivotally connected, as shown at 70, with collars 71 mounted on the piston stem between the two cylinders. These links coöperate with dogs 72 which are pivotally mounted, as shown at 73, in cavities 74 formed in the upper portion 75 of the base or foundation of the structure, this part 75 being mounted on the main base member 96. Each dog 72 is so arranged that when the corresponding piston is traveling outwardly in its cylinder the lower extremity of the link 69 engages a projection 75 on the dog and moves the latter to the dotted line 95 position (see Fig. 3), whereby the link moves idly. However, when the piston is making its return movement and just as the explosion occurs, the dog which has resumed the position shown by full lines in Fig. 3 and being out of the way allows the link 69 to drop into a recess 76 and engage an abutment 77, this engagement occurring the instant that the explosion takes place. This arrangement prevents any strain upon the piston operating mechanism as will be readily understood. The collars 71 are adjustable on the piston rod in order that they may be so positioned as to accommodate variations with reference to the inward travel of the pistons before the explosions occur for varying the degree of compression.

As illustrated in the drawing, provision is made for water cooling the cylinders, jackets 78 being provided which are in communication with inlet and outlet pipes 79 and 80.

From the foregoing description the use and operation of my improved pump will be readily understood. The pistons are reciprocated through the medium of the motor 16, whereby the shaft 17 is rotated and operates the crank wheel 19 through the medium of the worm gearing connection heretofore explained. This wheel is connected with the piston stem to reciprocate the pistons. When either piston has reached its inward limit of movement in one cylinder and begins its outward travel, it begins to draw a charge of explosive mixture into the compartment 15 thereof. At the same time

the other piston begins its inward travel, during which travel the explosion occurs and which may be so timed that the explosive mixture is compressed more or less within the cylinder. The construction, as arranged, as heretofore explained, assumes that the explosion will occur soon after the piston has commenced its inward travel. This may be varied, however, in order that 10 the explosive mixture within the cylinder may be considerably compressed before the explosive mixture is ignited. As soon as any explosion occurs, the explosive force through the medium of the connections heretofore explained acts on the water in the chamber 41 and causes the same to rise through the stand pipe 51 in a continuous stream, since the explosions which occur alternately in the two cylinders have sufficient 20 frequency to produce this result.

In operation the pistons move continuously forward during compression, explosion and scavaging. The lock mechanism, 69, 71, 77, is used only to relieve excessive strain from 25 the driving parts, 17, 18, 19 and 21, at the instant of explosion in case these parts are not deemed strong enough in themselves to withstand the strain. But the movement of the pistons is still continuously forward.

30 Each cylinder is provided with an oil cup or receptacle 81, whereby the inner walls of the cylinders are lubricated sufficiently for the purpose.

Having thus described my invention, what 35 I claim is:

1. An internal combustion compression pump comprising cylinders, pistons therein, means for introducing explosive mixture into the cylinders, means for igniting such mixture at properly timed intervals, a liquid supply source, a suitable chamber in communication with such source, conduits connecting the cylinders with said chamber, means for placing said chamber in connection with the atmosphere at the intervals between explosions, said means being adapted to break said communication with the atmosphere only at the times of explosion, and means independent of the explosions for operating the pistons.

2. An internal combustion compression pump comprising cylinders, pistons mounted to reciprocate therein, means for introducing explosive mixture to the cylinders, means for igniting such mixture at properly timed intervals, a suitable chamber in communication with a source of liquid supply, conduits connecting the cylinders with said chamber, a suitable standpipe in communication with the liquid chamber, and means for placing said chamber in connection with the atmosphere at the intervals between explosions, said means being adapted to break said communication with the atmosphere only at the times of explosion.

3. A pump of the class described comprising cylinders, pistons therein, means for introducing explosive mixture to the cylinders, means for alternately igniting the charges of explosive mixture in the cylinder at properly timed intervals, a suitable chamber in communication with the source of water supply, conduits connecting the explosion compartments of the cylinders with the said chamber, and means for mechanically placing said chamber in communication with the atmosphere at properly timed intervals, said means being adapted to break said communication with the atmosphere only at the times of explosion. 70 75 80

4. A pump of the class described comprising cylinders, pistons therein, a stem connecting the pistons, means for introducing explosive mixture to the cylinders, means for alternately igniting such mixture 85 in the cylinders at properly timed intervals, a suitable chamber in communication with a source of water supply, conduits connecting the explosion compartments of the cylinders with said chamber, and means for placing said chamber in communication with the atmosphere at properly timed intervals comprising a valve connected in operative relation with the piston stem. 90

5. A pump of the class described comprising two cylinders, each having check valve-controlled inlet and outlet ports, a water chamber, a passage leading from each outlet port to said chamber, the inlet ports being in communication with a source of 100 explosive mixture, pistons in the cylinders, means for igniting the explosive mixture in the cylinders at properly timed intervals, means independent of the explosive force for actuating the pistons, and means for 105 locking the pistons to relieve the mechanism from recoil stress due to the explosions in the cylinders. 95 100

6. A pump of the class described comprising two cylinders, each having check 110 valve-controlled inlet and outlet ports, a water chamber, a passage leading from each outlet port to said chamber, the inlet ports being in communication with a source of explosive mixture, pistons in the cylinders, 115 means for igniting the explosive mixture in the cylinders at properly timed intervals, means independent of the explosive force for reciprocating the pistons, said means being timed to cause the pistons to travel into the explosion compartments at the time of the explosions, and means timed to lock the pistons to relieve the piston operating mechanism from the recoil stress due to the 120 explosions. 125

7. A pump of the class described comprising two cylinders, pistons therein, a stem connecting the pistons, means for introducing explosive mixture to the cylinders, a water chamber having a check valve- 130

controlled opening in communication with the source of supply, means for conducting the explosive force to said chamber, a stand-pipe in communication with said chamber, means for automatically placing said chamber in communication with the atmosphere at properly timed intervals, and means for locking the pistons to relieve the piston operating mechanism from the recoil stress of the explosions.

8. A pump of the class described comprising two cylinders, pistons therein, a stem connecting the pistons, means for introducing explosive mixture to the cylinders, a water chamber having a check valve controlled opening in communication with the source of supply, means for conducting the explosive force to said chamber, a stand-pipe in communication with said chamber, means for automatically placing said chamber in communication with the atmosphere at properly timed intervals, and means for locking the pistons to relieve the piston operating mechanism from the recoil stress of the explosions, said means being arranged to be actuated from the piston stem and comprising links connected with said stem, coöperating pivoted dogs, and an abutment on which the dogs are mounted.

30 9. A pump of the class described, comprising cylinders, pistons mounted to reciprocate therein, means for introducing explosive mixture to the cylinders, means for alternately igniting the charges of explosive mixture in the cylinders at properly timed intervals, a chamber, conduits connecting the explosive compartments of the cylinders with the said chamber, and means for placing said chamber in communication with the atmosphere at the intervals between the explosions and for breaking the communication only at the times of explosion.

40 10. An internal combustion compression pump, comprising a cylinder, a piston mounted to reciprocate therein, means for introducing explosive mixture to the cylinder, means for igniting such mixture when the piston is at an intermediate stage of its forward movement, and means independent of the explosions in the cylinder for operating the piston, whereby the piston is moved forward continuously during compression, combustion and scavaging.

45 11. An internal combustion compression pump, comprising a cylinder, a piston mounted to reciprocate therein, means for introducing explosive mixture to the cylinder, means for igniting such mixture when the piston is at an intermediate stage of its forward movement, means independent of the explosions in the cylinder for operating the piston, whereby the piston is moved forward continuously during compression, combustion and scavaging, a chamber, and

a conduit connecting the cylinder with the chamber, whereby the products of combustion are conducted into said chamber.

5 12. An internal combustion compression pump, comprising a cylinder, a piston mounted to reciprocate therein, means for introducing explosive mixture to the cylinder, means for igniting such mixture when the piston is at an intermediate stage of its forward movement, means independent of the explosions in the cylinder for operating the piston, whereby the piston is moved forward continuously during compression, combustion and scavaging, a chamber in communication with a source of liquid supply, a conduit connecting the cylinder with the chamber, whereby the products of combustion are conducted into said chamber, and means for the discharge of liquid from said chamber through the medium of said products of combustion.

15 13. An internal combustion compression pump, comprising a cylinder, a piston mounted to reciprocate therein, means for introducing explosive mixture to the cylinder, means for igniting such mixture when the piston is at an intermediate stage of its forward movement, and means independent of the explosions in the cylinder for operating the piston, whereby the piston is moved forward continuously during combustion and scavaging.

20 14. An internal combustion compression pump, comprising a cylinder, a piston mounted to reciprocate therein, means for introducing explosive mixture to the cylinder, means for igniting such mixture when the piston is at an intermediate stage of its forward movement, means independent of the explosions in the cylinder for operating the piston, whereby the piston is moved forward continuously during combustion and scavaging, a chamber, and a conduit connecting the cylinder with the chamber, whereby the products of combustion are conducted into said chamber.

25 15. A pump of the class described, comprising cylinders, pistons mounted to reciprocate therein, means for introducing explosive mixture to the cylinders, means for alternately igniting the charges of explosive mixture in the cylinders at properly timed intervals, a chamber, conduits connecting the explosive compartments of the cylinders with the said chamber, and means for placing said chamber in communication with the atmosphere at the intervals between the explosions and for breaking the communication only at the times of explosion, and means independent of the explosions to reciprocate the piston.

In testimony whereof I affix my signature.

JOHN A. McINTYRE.
